UNITED STATES PATENT OFFICE.

ERNST SCHUSTER, OF BERLIN, GERMANY.

CALCULATING-MACHINE.

1,069,481.

Specification of Letters Patent.

Patented Aug. 5, 1913.

Application filed July 15, 1909. Serial No. 507,839.

To all whom it may concern:

Be it known that I, ERNST SCHUSTER, citizen of the German Empire, and a resident of Charlottenstrasse 87, Berlin, in the 5 Kingdom of Prussia, Germany, have invented certain new and useful Improvements in Calculating-Machines, of which the following is a specification.

My invention relates to improvements in 10 calculating machines, and more particularly to that class of calculating machines in which a setting mechanism is operatively connected with two registering mechanisms, which are adapted separately to register 15 products and the sums of such products. And the object of the improvements is to increase the working capacity of machines of this character. And with this object my invention consists of the matter described 20 hereinafter and particularly pointed out in the appended claims.

For the purpose of explaining the invention two examples embodying the same have been shown in the accompanying drawings 25 in which the same letters of reference have been used in all the views to indicate corresponding parts.

In said drawings, Figure 1, is a front elevation of the machine, Fig. 2, is a plan or 30 top view of the same, the cover being removed, Fig. 3, is a vertical cross-section taken on the line A—A of Figs. 1 and 2, Fig. 4, is the same cross-section showing the gears in the position for mixed calculation, 35 Fig. 5, is a side-view of the carriage of the machine, Fig. 6, is a fragmentary plan of the carriage, Fig. 7, is a detail view showing the construction of the shift levers for the transmission gears, Fig. 8, is a side view 40 of the machine, Fig. 9, is a horizontal cross-section taken on the line B—B of Fig. 8, Fig. 10, is a vertical cross-section of the machine taken on the line B—B of Figs. 1 and 2, and illustrating the carrying or tens- 45 transfer mechanism, Fig. 11, is a fragmentary plan of Fig. 10, the casing of the machine being partly broken away, Figs. 12 and 13, are detail views of the tens-transfer or carrying mechanism of the second register- 50 ing mechanism, Fig. 14, is a vertical cross-section of a machine showing a modification of the mechanism illustrated in Figs. 1 to

13, Fig. 15, is a fragmentary front view of the modification shown in Fig. 14, a part of the casing of the machine being broken 55 away, and Fig. 16, is a fragmentary horizontal cross-section of the same taken on the line D—D of Fig. 14.

In the following my invention is described as used in a machine, the general construction of which is shown in the U. S. patent of C. Hamann, No. 772,935, granted Oct. 25, 1904.

Referring to the example illustrated in Figs. 1 to 13, the calculating-mechanism is 65 located within a casing 1. Within the lower part of the latter a carriage 2 is guided in suitable grooves of the base plate of the machine. By means of handles 4 projecting through slots 3 of the casing 1 70 the numbers are set on adjusting disks 5, and by turning a crank 65 they are transmitted through the intermediary of gears 6 mounted on shaft 6¹ to the registering mechanism 7 comprising number wheels 7¹ and 75 pinions 7². Below the registering mechanism 7 I provide a second registering mechanism 8 comprising number-wheels 8¹ and pinions 8², which are adapted to be operated from the gears 6 through the intermediary 80 of trains of gears 9, 10 and 11 carried by shafts 9¹, 15 and 12 respectively. The shafts 12 and 15 are slidably supported in the side walls of the carriage 2, as indicated in Figs. 6 and 9. The shaft 6¹ of the number-wheels 85 8¹ carries a rocking lever 13 which with one of its ends loosely engages in a groove 70 of the shaft 12 and with its other end projects through a slot 71 of the casing 1, where it carries a key 14, as is most clearly shown 90 in Figs. 1, 2 and 6.

The longitudinally shiftable shaft 15 carrying the gears 10 projects through a hole in the side wall of the casing 2, and its projecting end is engaged by a shift lever 17 95 having its fulcrum at 16 and provided with a handle 18. (Figs. 2, 5, 6, 8 and 9.) By shifting the lever 17 the gears 10 can be brought in or out of engagement with the gears 9 and 11, so that the said gears can 100 either be connected with or disconnected from each other. Therefore, if the number wheels 8¹ show a certain number through their peep holes, as a result of a calculation,

and the gears 10 are shifted in such a way as to break the connection between the gears 9 and 11, further calculations can be made, the result of which appears exclusively on the figure wheels 7¹. If it is desired to register one of said calculations also on the figure wheels 8¹, the lever 17 is again shifted into its original position, so that the gears 9 and 11 are again connected with each other.

10 The figure wheels 7¹ and 8¹ are provided at their peripheries with numerical characters from "1" to "9" and the "0" sign, and if the wheels are in the position shown in Fig. 3, the numbers transmitted thereto appear 15 in ascending succession in both registering mechanisms 7 and 8. If, however, the shaft 12 is raised by depressing the key 14, the gears 11 are disengaged from the gears 10 and brought in direct engagement with the 20 pinions 7² and 8² of the registering mechanisms 7 and 8. Thereby the direction of rotation of the number wheels 8¹ is reversed, so that the numbers appear in descending succession, and the number wheels 8¹ register a subtraction of the number which on 25 the number wheels 7¹ is registered as an addition. To prevent the shaft 12 from dropping downward a rocking lever 20 carrying a key 21 is fulcrumed at 19, which with its 30 key carrying arm projects through a slot 72 in the casing 1, and at its other end is formed with a nose 22 providing a lock for the said shaft. The levers 13 and 20 are connected with each other by a spring 23.

35 If the shaft 12 is raised, the nose 22, under the action of the spring 23, engages the shaft 12 at its lower side, so as to lock the same in its raised position, as shown in Fig. 4. To disengage the gear 11 from the pinion 7², 40 the key 21 is depressed, whereby the nose 22 is retracted from below the shaft 12, and the latter drops into its original position under the action of the spring 23.

The tens-transfer or carrying mechanism 45 for the number wheels 7¹ can be constructed in any known or preferred way. However, the number wheels 8¹ require independent carrying means, and these carrying means must be operated after the carrying operation in the number wheels 7¹ has been completed. For this purpose, a segment or disk 24 having teeth about part of its circumference is mounted on the shaft 5¹ carrying the adjusting disks 5. (Figs. 2, 10 and 11.)

50 By means of the said toothed segment spur gears 25 and 26 mounted on the casing 1 can be rotated. Below the gear 26 there is an elongated toothed gearing 27 extending over the whole length of the adjusting device.

55 On the shiftable carriage 2 gears 28, 29 and 30 are mounted which are in engagement with one another. The spur gears 28 and 26 both mesh with the elongated gear 27. The gear 30 meshes with a spur gear 32 60 keyed to a shaft 31 located below the num-

ber wheels 8¹. By these gears the shaft 31 is rotated upon actuation of the crank of the machine. The number of the teeth of the said gears is such that upon rotation of the disk 24 over one half the angular extent of its teeth the shaft 31 performs a complete revolution. By reason of the elongated gear 27 the transmission of the rotation is effected independently of the position of the carriage 2 and its registering mechanisms 7 75 and 8. The shaft 31 carries laterally movable pins 33 which, by notches 34 and 35, are held in one of two positions, and which extend between adjacent number wheels 8¹. (Figs. 10 to 13.) Adjacent to the "0" signs 80 the number wheels are formed with lugs 36. Below the shaft 31 there is a stationary shaft 37 having recesses 39 with V-shaped faces 38.

The teeth of the disk 24 are so located, 85 that in the position of rest the toothed gear 25 engages in the middle of the toothed segment of the disk 24, so that upon rotation of the said disk in either direction at the beginning and at the end of a complete revolution of the disk the shaft 31 has performed a full revolution, whether the crank 65 of the machine is operated to perform positive or negative calculations. During the first part of its revolution the disk 24 90 does not exert any influence on the number wheels. Thereupon the number wheels 7¹ are acted upon by the adjusting disks, while the gears 25 to 30 remain stationary. Near the end of the rotation of the disk 24 its 95 teeth come again into engagement with the gear 25. If in the course of the transmission of numbers from the number wheels 8¹ to the number wheels 7¹ one of the wheels has passed from "9" to "0," or vice versa, 100 the lug 36 forces the proper pin 33 sidewise and into the path of the pinion 8² of the adjacent number wheel 8¹, and upon rotation of the shaft 31, the said wheel is moved forward a distance of two numbers by means 105 of the pin 33. If the rotation is continued, the pin 33 rides over the V-shaped face 38, and into the recess 39, so that it passes again over from its position within the notch 35 into that within the notch 34.

110 By arranging the pins 33 on the shaft 31 successively one behind the other, the carrying operation takes place successively in the number wheels, of the different denominations.

115 If one set of the number wheels is reset, and the intermediate gears 10 have inadvertently not been thrown out of operation, also the second set of number wheels would unintentionally be reset. To avoid this, 120 means are provided, whereby, if one of the registering mechanisms is set to zero, the intermediate gears connecting both registering mechanisms are automatically thrown out of operation, so that a mistake can not 125 130

occur. This mechanism is shown in Figs. 2, 6, 8, and 9.

On the outside of the carriage 2 supporting the number wheels a plate 42 is hinged at 41. The said plate forms a rocking lever, which with one end 43 fits loosely on the shaft 15 at the rear of a sleeve 44. As stated before, the shaft 15 is also engaged by the lever 17. The other part of the plate 42 is formed with two eyes 45 and 46 which embrace the ends of the shafts 67 and 66 of the number wheels 7 and 8, which ends project through the side-wall of the carriage. By a spring 47 the said eyes 45 and 46 are normally held away from the side-wall of the carriage, while the end 43 of the plate is forced toward the same. Thereby the shifting movement of the shaft 15 is not interfered with, so that the said shaft can be so adjusted by the lever 17, that the gears 10 are either in or out of engagement with the gears 9 and 11, as described above. At their ends the shafts 67 and 66 of the number wheels 7¹ and 8¹ are provided with pins 48 and 49 having projections 50 bent laterally and at right angles thereto. The said pins are normally engaged within recesses 51 of rings 52 secured to the side wall of the carriage. The faces of said notches are inclined outward and in the direction of the rotation of the shafts, as is indicated in Fig. 8 by the numerals 51¹, 51².

Adjacent to the pins 48 and 46 the eye sections 45 and 46 of the plate 42 are also formed with an indentation, and the margin 53 coinciding with the inclined face of the ring 52 is bent inward, so that upon rotation of the shafts the studs 50 can ride on the margin of the eyes 45 and 46. For the purpose of resetting the number wheels 7¹, their shaft 67 is rotated in the usual way by means of a crank 54. By the action of the pin 48 projected from the notch 51 by the inclined face of the ring 52 the shaft is shifted laterally, so that the number wheels are moved backward into their zero position. In the same way the shaft 66 of the number wheels 8 carries a crank 55 which is preferably located at the opposite side of the carriage. The operation of the resetting mechanism is known in the art and needs no description.

If a calculation has been made the result of which, by reason of the intermediate gears 10 being thrown into operation, is different in both number wheels, the zero setting operation performed in one of the registering devices would also result in the zero setting operation being performed in the other device, because both devices are connected by the intermediate gears 10. Therefore, if it is desired to reset only one of the said devices, the gears 10 must be thrown out of operation by means of the lever 17. However, by means of the mechanism described

this is done automatically, so that an error can not occur. If for the purpose of performing a zero setting operation the crank 54 or 55 is turned, the end 50 of the pins 48 or 49, as the case may be, by the displacement of the shaft by means of the said pin 48 or 49, will ride on the margin 53 of the eye 45 or 46, so that the latter is forced toward the wall of the casing. Thereby the opposite end 43 is removed from the side wall of the carriage, and it carries along the shaft 15 through the intermediary of the sleeve 44, so that the gears 10 are shifted laterally and thrown out of engagement with the gears 9 and 11. At the end of the rotation the pin 48 or 49 is again projected into the recess of the ring 52, and the plate 42 is pressed backward into its original position by the spring 47, so that the gears 10 are again brought into engagement with the gears 9 and 11.

In the example illustrated in Figs. 14 to 16 the intermediate gears 110 are also located on a laterally shiftable shaft 115. However, the shaft of the intermediate gears 111 is stationary, the shifting movement of the registering mechanism being performed in the following way: The number wheels 108 of the registering mechanism 108 are each provided with two rows of numerical characters, the characters of both rows being arranged in opposite order. The peep holes are covered by a sliding shutter 57 which is adapted to display the characters of either one of the rows at a time. By means of a button 58 the said sliding shutter can be shifted, its movement being limited by a pin 60 projecting through a slot 59. If the shutter 57 is so adjusted as to display the right hand series of characters, the numbers of both registering devices appear in the ascending order. If, however, the button is shifted, the numbers of the second registering mechanism appear in the descending order. Therefore, all the calculations can be made in the same way as in the example described with reference to Figs. 1 to 13.

In front of the registering mechanism 108 a shaft 61¹ is located which carries gears 61 partly projecting through slots 61² of the casing. By the said gears the wheels 108¹ can be directly turned and adjusted to show a certain number in the registering mechanism 8.

From the forgoing description it will be understood that the working capacity of machines of the character specified is greatly increased. And more particularly, in my improved machine one of the registering mechanisms can be operated while the other one is entirely thrown out of operation, and results can be obtained directly by the operation of the setting mechanism and without first setting one of the register-

ing mechanisms to zero. By thus constructing my improved machine, I am not only able to sum up products, but also to perform mixed calculations of positive and negative character in both registering mechanisms. For example, by means of my improved machine I am able to interrupt an addition of products made in one of the registering mechanisms and to perform simple calculations in the other registering mechanism. Furthermore, the sums of any desired number of products can be taken apart from the sum of all the products, and finally, a product can be subtracted from a sum, and simultaneously the difference of the sum and the product can be displayed.

I claim:

1. In a calculating machine, the combination with the setting mechanism adapted to have values set thereon, of a plurality of registering mechanisms, means independent of the setting operation and operative in both directions to transmit the values set on the setting mechanism to said registering mechanisms, and means to throw one of said registering mechanisms out of coöperation with the setting mechanism.

2. In a calculating machine, the combination with a setting disk having a plurality of normally inoperative teeth, and means to move any number of said teeth into operative position, of a plurality of registering mechanisms adapted to be operated upon rotation of said disk by the operative teeth, means to rotate said disk, and means to throw one of said registering mechanisms out of coöperation with the teeth of said setting disk.

3. In a calculating machine, the combination with a setting disk having a plurality of normally inoperative teeth, and means to move any number of said teeth into operative position, of a plurality of registering mechanisms adapted to be operated upon rotation of said disk by the operative teeth, means operative in both directions to rotate said disk, and means to throw one of said registering mechanisms out of coöperation with the teeth of said setting disk.

5. In a calculating machine, the combination with the setting mechanisms, of two registering mechanisms, sets of gears connecting said setting mechanisms with said registering mechanisms, and means to shift one of said sets of gears laterally and out of engagement with the coöperating gears.

6. In a calculating machine, the combination with the setting mechanism adapted to have values set thereon, of a plurality of registering mechanisms, sets of gears connecting said setting mechanism with said registering mechanisms, means independent of the setting operation to transmit the values set on the setting mechanism through the intermediary of said gears to said regis-

tering mechanisms, and means to shift one of said sets of gears laterally and out of engagement with the coöperating gears.

6. In a calculating machine, the combination with the setting mechanism adapted to have values set thereon, of a plurality of registering mechanisms, means independent of the setting operation and operative in both directions to transmit the values set on the setting mechanism to said registering mechanisms, and means coöoperating with one of said registering mechanisms only to cause the coöperating registering mechanism to display calculations of a character opposite to that of the calculations performed in another registering mechanism.

7. In a calculating machine, the combination with the setting mechanism adapted to have values set thereon, of a plurality of registering mechanisms, means independent of the setting operation to transmit the values set on the setting mechanism to said registering mechanisms, and means to reverse the direction of the transmission of the values set on the setting mechanism to one of said registering mechanisms.

8. In a calculating machine, the combination with the setting mechanism, of two registering mechanisms an operative connection between said setting mechanism and one of said registering mechanisms, two trains of gears of different numbers of gears adapted to connect said setting mechanism and second registering mechanism, and means to throw either one of said gears into operation.

9. In a calculating machine, the combination with the setting mechanism adapted to have values set thereon, of two registering mechanisms, an operative connection between said setting mechanism and one of said registering mechanisms, two trains of gears of different numbers of gears adapted to connect said setting mechanism and second registering mechanism, means independent of the setting operation to transmit the values set on the setting mechanism through the intermediary of said operative connection and trains of gears to said registering mechanisms, and means to throw either one of said gears into coöperation with said second setting mechanism.

10. In a calculating machine, the combination with the setting mechanism, of two registering mechanisms, an operative connection between said setting mechanism and one of said registering mechanisms, two trains of gears of different numbers of gears adapted to connect said setting mechanism and second registering mechanism, and a rock shaft carrying a set of gears adapted to be interposed between the gears of either one of said trains of gears.

11. In a calculating machine, the combination with the setting mechanism adapted

120

125

130

- to have values set thereon, of two registering mechanisms, an operative connection between said setting mechanism and one of said registering mechanisms, two trains of 5 gears of different numbers of gears adapted to connect said setting mechanism and second registering mechanism, means independent of the setting operation to transmit the values set on the setting mechanism through the intermediary of said operative connection and trains of gears to said registering mechanisms, and a rock shaft carrying a set of gears adapted to be interposed between the gears of either one of said trains of 10 gears.
12. In a calculating machine, the combination with the setting mechanism, of two registering mechanisms, an operative connection between said setting mechanism and one of said registering mechanisms, two trains of 15 gears of different numbers of gears adapted to connect said setting mechanism and second registering mechanism, a rock shaft carrying a set of gears adapted to be interposed between the gears of either one of said trains of gears, and means to lock said rock shaft in its rocked position.
13. In a calculating machine, the combination with the setting mechanism adapted to have values set thereon, of two registering mechanisms, an operative connection between said setting mechanism and one of said registering mechanisms, two trains of 20 gears of different numbers of gears adapted to connect said setting mechanism and second registering mechanism, a rock shaft carrying a set of gears adapted to be interposed between the gears of either one of said trains of gears, and means to lock said rock shaft in its rocked position.
14. In a calculating machine, the combination with the setting mechanism, of two registering mechanisms, an operative connection between said setting mechanism and one of said registering mechanisms, two trains of 25 gears of different numbers of gears adapted to connect said setting mechanism and second registering mechanism, means independent of the setting operation to transmit the values set on the setting mechanism through the intermediary of said operative connection and trains of gears to said registering mechanisms, and a rock shaft carrying a set of gears adapted to be interposed between the gears of either one of said trains of gears, and means to lock said rock shaft in its rocked position.
15. In a calculating machine, the combination with the setting mechanism adapted to have values set thereon, of two registering mechanisms, an operative connection between said setting mechanism and one of said registering mechanisms, two trains of 30 gears of different numbers of gears adapted to connect said setting mechanism and second registering mechanism, a rock shaft carrying a set of gears adapted to be interposed between the gears of either one of said trains of gears, and means to lock said rock shaft in its rocked position.
16. In a calculating machine, the combination with the setting mechanism, of two registering mechanisms, an operative connection between said setting mechanism and registering mechanisms, resetting devices for each of said registering mechanisms and operable independently of said setting mechanism, and means to throw one of said registering mechanisms out of coöperation with the setting mechanism.
17. In a calculating machine, the combination with the setting mechanism, of two registering mechanisms, sets of gears connecting said setting mechanism with said registering mechanisms, resetting devices for each of said registering mechanisms and operable independently of said setting mechanism, and means to shift one of said sets of gears laterally and out of engagement with the coöoperating gears.
18. In a calculating machine, the combination with the setting mechanism, of two registering mechanisms, an operative connection between said setting mechanism and registering mechanisms, resetting devices for each of said registering mechanisms and operable independently of said setting mechanism, and means to reverse the direction of the transmission of the values set on the setting mechanism to one of said registering mechanisms.
19. In a calculating machine, the combination with the setting mechanism, of two registering mechanisms, an operative connection between said setting mechanism and one of said registering mechanisms, two trains of gears of different numbers of gears adapted to connect said setting mechanism and second registering mechanism, resetting devices for each of said registering mechanisms and operable independently of said setting mechanisms, and means to throw either one of said trains of gears into coöperation with said setting mechanism and second registering mechanism.
20. In a calculating machine, the combination with the setting mechanism adapted to have values set thereon, of a plurality of registering mechanisms, means independent of the setting operation to transmit the

values set in the setting mechanism to said registering mechanisms, resetting devices for each of said registering mechanisms and operable independently of said setting mechanism, and means to throw one of said registering mechanisms out of coöperation with the setting mechanism.

21. In a calculating machine, the combination with the setting mechanism adapted to have values set thereon, of a plurality of registering mechanisms, means independent of the setting operation to transmit the values set on the setting mechanism to said registering mechanisms, resetting devices for each of said registering mechanisms and operable independently of said setting mechanism, and means to reverse the direction of the transmission of the values set on the setting mechanism to one of said registering mechanisms.

22. In a calculating machine, the combination with the setting mechanism, and the registering mechanism, of a carrying mechanism for the registering mechanism comprising a rotary shaft extending longitudinally of and adjacent to the number wheels and pinions of said registering mechanism, shiftable pins carried by said shaft, means on said number wheels adapted to shift the pins into engagement with the pinions of the number wheels of the next higher denomination, and means to remove the pins into their normal positions.

23. In a calculating machine, the combination with the setting mechanism, and the registering mechanism, of a carrying mechanism for the registering mechanism comprising a rotary shaft extending longitudinally of and adjacent to the number wheels and pinions of said registering mechanism, shiftable pins carried by said shaft, said pins being mounted within slots made in said shaft and adapted to rest within one of two notches provided at the bottom of each of said slots, means on said number wheels adapted to shift the pins into engagement with the pinions of the number wheels of the next higher denomination, and means to remove the pins into their normal positions.

24. In a calculating machine, the combination with the setting mechanism, and the registering mechanism, of a carrying mechanism for the registering mechanism comprising a rotary shaft extending longitudinally of and adjacent to the number wheels and pinions of said registering mechanism, shiftable pins carried by said shaft, means on said number wheels adapted to shift the pins into engagement with the pinions of the number wheels of the next higher denomination, and a rotary shaft extending parallel and adjacent to said first named shaft, and

having recesses in the path of said pins when in their normal positions, each of said recesses having an inclined face adapted to engage its pin when in its shifted position and to move the same into its normal position.

25. In a calculating machine, the combination with the setting mechanism, and the registering mechanism, of a carrying mechanism for the registering mechanism comprising a rotary shaft extending longitudinally of and adjacent to the number wheels and pinions of said registering mechanism, shiftable pins carried by said shaft, said pins being mounted within slots made in said shaft and adapted to rest within one of two notches provided at the bottom of each of said slots, means on said number wheels adapted to shift the pins into engagement with the pinions of the number wheels of the next higher denomination, an operative connection between the shaft carrying the setting mechanism and the pin carrying shaft adapted to rotate the latter during the last part of the operation of said setting mechanism, and means to remove the pins into their normal positions.

26. In a calculating machine, the combination with the setting mechanism, and a longitudinally shiftable registering mechanism, of a rotary shaft extending longitudinally of and adjacent to the number wheels and pinions of said registering mechanism, shiftable pins carried by said shaft and co-operating with said number wheels, means on said number wheels adapted to shift the pins into engagement with the pinions of the number wheels of the next higher denomination, means to move the said pins back into their normal positions, and an elongated spur gear operatively connected with the said setting mechanism and with the pin carrying shaft and adapted to transmit the motion of said setting mechanism to said pin carrying shaft in any position of the registering mechanism.

27. In a calculating machine, the combination with the setting mechanism, and two registering mechanisms operatively connected with said setting mechanism, of zero setting mechanisms for each of said registering mechanisms, and automatic means to disconnect said registering mechanisms upon operation of one of said zero setting mechanisms.

28. In a calculating machine, the combination with the setting mechanism, of two registering mechanisms, sets of gears connecting said setting mechanism with said registering mechanisms, a longitudinally shiftable shaft carrying a set of gears connecting both registering mechanisms, a zero setting device for each of said registering mechanisms operated by turning the shafts carrying the number wheels, a rocking ele-

ment adapted to be rocked upon rotation of either one of the number wheel shafts and so connected with said shiftable shaft as to be adapted when so rocked to shift said shiftable shaft laterally and thereby to break connection between said registering mechanisms.

In testimony whereof I affix my signature in presence of two witnesses.

ERNST SCHUSTER.
